UNITED STATES PATENT OFFICE

147,886

DESIGN FOR A BRACELET

Herman Bogoff, Chicago, Ill.

Application October 14, 1946, Serial No. 133,926

Term of patent 7 years

(Cl. D45—4)

To all whom it may concern:

Be it known that I, Herman Bogoff, a citizen of the United States, residing in Chicago, in the county of Cook and State of Illinois, have invented a new, original, and ornamental Design for a Bracelet, of which the following is a specification, reference being had to the accompanying drawing, forming part thereof.

Fig. 1 is a front elevational view of a bracelet showing my design, and

Fig. 2 is a side view thereof.

I claim:

The ornamental design for a bracelet, substantially as shown.

HERMAN BOGOFF.
